UNITED STATES PATENT OFFICE.

ALBERT EDWARD JONES, OF WESTMINSTER, LONDON, ENGLAND, ASSIGNOR TO THE
WHITEHEAD TORPEDO COMPANY LIMITED, OF WESTMINSTER, ENGLAND.

GYROSCOPIC STEERING APPARATUS OF AUTOMOBILE TORPEDOES.

Application filed March 20, 1924. Serial No. 700,645.

To all whom it may concern:

Be it known that I, ALBERT EDWARD JONES, a subject of the King of Great Britain, residing at 8 Great George Street, 6 Westminster, in the county of London, England, have invented certain new and useful Improvements in or Relating to the Gyroscopic Steering Apparatus of Automobile Torpedoes, of which the following is a 10 specification.

This invention relates to gyroscopic steering apparatus for automobile torpedoes, of the kind in which the flywheel, after it has been rapidly spun up to the required speed, 15 is maintained spinning by one or more jets of air issuing from one or more nozzles and impinging upon buckets or pockets formed on or in the flywheel. In such apparatus as heretofore constructed the nozzles from 20 which the jets of air issue have been mounted on the outer or vertical gimbal ring and in consequence of the relative movement occurring, during the running of the torpedo, between the said gimbal ring and the inner 25 or horizontal gimbal ring in which the flywheel is rotatably mounted, the direction of the jets of air in relation to the plane of rotation of the flywheel is constantly varying, whereby a couple is produced which tends 30 to deflect the vertical gimbal ring.

According to the present invention the above-mentioned defect is obviated by fixing the nozzles to the inner or horizontal gimbal ring so that the direction of the jets always 35 remains constant with respect to the plane of rotation of the flywheel despite the relative movement that occurs between the gimbal rings. The said nozzles preferably pass axially through the trunnions of the said 40 inner gimbal ring and their receiving ends surround or are arranged in close proximity to (but are not connected with) the ends of air supply nozzles carried by the outer or vertical gimbal ring. The spinning of the 45 flywheel is preferably started by air supplied under high pressure to a large bore nozzle (preferably with a flared mouth) which is carried by the outer gimbal ring, the air from this nozzle impinging upon the 50 aforesaid buckets or pockets of the flywheel; the supply conduit for this nozzle is formed in the supporting frame and the receiving end of the nozzle is arranged in close proximity to, but not connected with, the con- 55 tiguous end of the supply conduit, the ar-

angement being such that when the gimbal rings are unlocked in the usual manner and the air supply to the said nozzle is cut off, the outer gimbal ring can move with respect to the supporting frame.

Another feature of the invention relates to an improved device for obtaining "angle fire"; this improved device, which is of a simpler character than similar devices heretofore proposed, comprises a slide or piston valve disposed in an angularly adjustable ported valve casing and connected to a crank pin carried by the outer gimbal ring, preferably by the top vertical pivot thereof. The connection may be effected by means of a stirrup member which engages with the ends of the valve stem and has a recess to receive the aforesaid crank pin. The said valve casing, which is preferably conical, is arranged co-axial with the pivotal axis of the outer gimbal ring and has an axial air supply passage and two parallel passages leading to the ends of the steering cylinders, the exhaust ports being preferably formed in one side of the valve chest. The said passages communicate with supply and delivery conduits in the supporting frame and these conduits are so arranged that communication between them and the passages is maintained during angular displacement of the 70 casing.

Still another feature of the invention consists in mounting on the breech door of a torpedo tube a setting device for the "angle fire" device of a torpedo and in providing 90 one or more detachable connections between this device and an adjusting spindle of the "angle fire" device which spindle extends beyond the torpedo shell.

In order that the said invention may be 95 clearly understood and readily carried into effect, the same will now be described more fully with reference to the accompanying drawings, in which:—

Figure 1 is a sectional end elevation shewing a gyroscope constructed in accordance with the present invention,

Figure 2 is a section taken approximately on the line 2, 2 of Figure 1, and

Figure 3 is a diagrammatic view shewing the preferred means of adjusting the "angle fire" device from the breech end of the launching tube.

A is the gyroscope flywheel. B is the inner or horizontal gimbal ring in which the 110

flywheel is rotatably mounted, C is the outer or vertical gimbal ring in which the inner gimbal ring B is trunnioned at b, b and D is the frame in which the outer gimbal ring 5 C is trunnioned at c, c.

The inner gimbal ring B has fixed to it two air nozzles one of which is shewn at b¹ and the other is arranged diametrically opposite, the latter pointing upwardly in contradistinction to the downward pointing of the nozzle b¹. Each of these nozzles passes axially through its contiguous trunnion b and its end receives the tapered end of a supply nozzle c' carried by the outer gimbal 10 ring C co-axially with the trunnion b. These supply nozzles form extensions of pipes c², c² which communicate with conduits c³, c³ in the outer gimbal ring. These conduits terminate in an annular recess c⁴ 15 which in turn communicate with an axial hole c⁵ in the lower vertical pivot c of the outer gimbal ring, air under pressure being conveyed to this axial hole through the passages c⁶ and c⁷. The flywheel A is formed 20 with pockets (some of which are shewn at a in Figure 1) with which the jets of air issuing from the nozzles b¹ co-operate to maintain the spinning of the flywheel.

E is the aforesaid large bore nozzle carried by the outer gimbal ring C and supplied with air under high pressure, the air that issues from this nozzle co-operating with the pockets a of the flywheel A to start the latter spinning. The frame D has an air 30 supply conduit d the mouth d¹ of which is situated immediately above the entrance of the nozzle E when the outer gimbal ring is in its normal position.

F is the aforesaid piston valve and F¹ is 40 the angularly adjustable valve casing in the lower part of which the said valve is slidably disposed. This valve casing is conical and is formed with three circumferential grooves f, f¹, f² which, at all angular positions of the valve casing, communicate with passages f^x, f^{1x} and f^{2x} in the valve casing and with passages F^x, F^{1x} and F^{2x} in the frame D. The passages f^{1x} and F^{1x} carry the supply of air under pressure to the valve 45 F, the passages f^x and F^x convey the air under pressure from the valve to one end of the steering cylinder F⁰ and the passages f^{2x} and F^{2x} convey air under pressure from the valve to the other end of the steering cylinder, it being understood that the valve F 50 establishes communication between the passage f^{1x} and the passage f^x or the passage f^{2x}, or shuts off communication between these passages, according to the position of the valve. Exhaust ports f³, f⁴ are provided for placing to exhaust whichever of the passages f^x, f^{2x} is not connected to the supply passage f^{1x}. The valve F is connected to a stirrup member F³ which has a recess to receive a pin f² projecting upwardly from the upper 55

vertical pivot c of the outer gimbal ring C in a position slightly removed from the axis of this pivot (see Figure 1) so as to constitute a crank pin. Thus during relative movement between the valve casing F¹ and the outer gimbal ring C, the valve F is moved longitudinally to control the steering of the torpedo. The upper end of the valve casing F¹ has connected to it a worm wheel F⁴ between which and the seating for the casing F¹ (which seating forms a part of the steering cylinder F⁰ and of the frame D) is a compression spring f⁵ serving to hold the valve casing in contact with its seating. Meshing with this worm wheel is a worm G carried by a spindle g (see Figure 3) arranged parallel to the axis of the torpedo. The rear part of this spindle passes through a stuffing box on the torpedo shell and is detachably connected at g¹ to a setting spindle G¹. The latter spindle is carried by the launching tube G² and its rear end is detachably connected at g^x to a short spindle G^x which projects through the breech door g² of the tube and has a pointer G³ movable over a graduated angle fire dial g³ on the door. The said setting spindle G¹ is made capable of ready removal to permit a torpedo to be introduced into the tube and is so disposed when in position as to be clear of the torpedo tail and the rotating propeller blades. It will be understood that the part g^x serves to establish a connection between the short spindle G^x and the setting spindle G¹ by the act of closing the breech door g². It will also be understood that this feature of the invention can be employed in connection with other forms of angle fire devices of similar type.

What I claim and desire to secure by Letters Patent of the United States is:—

1. In gyroscopic steering apparatus for automobile torpedoes, the combination with the flywheel, the inner gimbal ring, the outer gimbal ring and the frame supporting the latter ring, of a nozzle fixed to said inner gimbal ring for directing a jet of air under pressure on to operative surfaces on said flywheel to maintain the latter spinning during the run of the torpedo, the receiving end of said nozzle being arranged axially within one of the trunnions of the inner gimbal ring, and an air supply nozzle on said outer gimbal ring, the latter nozzle projecting into, but being unconnected with, the receiving end of the first mentioned nozzle.

2. In gyroscopic steering apparatus for automobile torpedoes, the combination with the flywheel, the inner gimbal ring, the outer gimbal ring and the frame supporting the latter ring, of a large bore nozzle on said outer gimbal ring for directing air under high pressure on to operative surfaces on said flywheel for starting the spinning of the flywheel, and a nozzle fixed to said inner

- gimbal ring for directing a jet of air under pressure on to said operative surfaces to maintain the flywheel spinning during the run of the torpedo.
5. In gyroscopic steering apparatus for automobile torpedoes, the combination with the flywheel, the inner gimbal ring, the outer gimbal ring and the frame supporting the latter ring, of a large bore nozzle on said outer gimbal ring with its receiving end eccentric with respect to the pivotal axis of the outer gimbal ring, for directing air under high pressure on to operative surfaces on said flywheel for starting the spinning of the flywheel, and a nozzle fixed to said inner gimbal ring for directing a jet of air under pressure on to said operative surfaces to maintain the flywheel spinning during the run of the torpedo.
10. In an "angle fire" device for automobile torpedoes, the combination with the flywheel of the gyroscope, the inner gimbal ring, the outer gimbal ring, the frame supporting the latter ring, and the steering cylinder, of a reciprocating valve for controlling the supply of air under pressure to the ends of said steering cylinder, a valve casing which is arranged coaxially with the pivotal axis of said outer gimbal ring and in the inner part of which said valve is slidably and transversely disposed, a crank pin carried by said outer gimbal ring, and a stirrup member interposed between said crank pin and said valve for transmitting movement from said crank pin to said valve with respect to the valve casing when relative movement occurs between said valve casing and said outer gimbal ring.
15. In an "angle fire" device for automobile torpedoes, the combination with the flywheel of the gyroscope, the inner gimbal ring, the outer gimbal ring, the frame supporting the latter ring, and the steering cylinder, of a reciprocating valve for controlling the supply of air under pressure to the ends of said steering cylinder, a valve casing which is arranged coaxially with the pivotal axis of said outer gimbal ring and in the inner part of which said valve is slidably and transversely disposed, a crank pin carried by said outer gimbal ring, and a stirrup member interposed between said crank pin and said valve for transmitting movement from said crank pin to said valve with respect to the valve casing when relative movement occurs between said valve casing and said outer gimbal ring.
20. In an "angle fire" device for automobile torpedoes, the combination with the flywheel of the gyroscope, the inner gimbal ring, the outer gimbal ring, the frame supporting the latter ring, and the steering cylinder, of a reciprocating valve for controlling the supply of air under pressure to the ends of said steering cylinder, a valve casing which is arranged coaxially with the pivotal axis of said outer gimbal ring and in the inner part of which said valve is slidably and transversely disposed, a crank pin carried by said outer gimbal ring, and a stirrup member interposed between said crank pin and said valve for transmitting movement from said crank pin to said valve with respect to the valve casing when relative movement occurs between said valve casing and said outer gimbal ring.
25. In an "angle fire" device for automobile torpedoes, the combination with the flywheel of the gyroscope, the inner gimbal ring, the outer gimbal ring, the frame supporting the latter ring, and the steering cylinder, of a reciprocating valve for controlling the supply of air under pressure to the ends of said steering cylinder, a valve casing which is arranged coaxially with the pivotal axis of said outer gimbal ring and in the inner part of which said valve is slidably and transversely disposed, a crank pin carried by said outer gimbal ring, and a stirrup member interposed between said crank pin and said valve for transmitting movement from said crank pin to said valve with respect to the valve casing when relative movement occurs between said valve casing and said outer gimbal ring.
30. In an "angle fire" device for automobile torpedoes, the combination with the flywheel of the gyroscope, the inner gimbal ring, the outer gimbal ring, the frame supporting the latter ring, and the steering cylinder, of a reciprocating valve for controlling the supply of air under pressure to the ends of said steering cylinder, a valve casing which is arranged coaxially with the pivotal axis of said outer gimbal ring and in the inner part of which said valve is slidably and transversely disposed, a crank pin carried by said outer gimbal ring, and a stirrup member interposed between said crank pin and said valve for transmitting movement from said crank pin to said valve with respect to the valve casing when relative movement occurs between said valve casing and said outer gimbal ring.
35. In an "angle fire" device for automobile torpedoes, the combination with the flywheel of the gyroscope, the inner gimbal ring, the outer gimbal ring, the frame supporting the latter ring, and the steering cylinder, of a reciprocating valve for controlling the supply of air under pressure to the ends of said steering cylinder, a valve casing which is arranged coaxially with the pivotal axis of said outer gimbal ring and in the inner part of which said valve is slidably and transversely disposed, a crank pin carried by said outer gimbal ring, and a stirrup member interposed between said crank pin and said valve for transmitting movement from said crank pin to said valve with respect to the valve casing when relative movement occurs between said valve casing and said outer gimbal ring.
5. In an "angle fire" device for automobile torpedoes, the combination with the flywheel of the gyroscope, the inner gimbal ring, the outer gimbal ring, the frame supporting the latter ring, and the steering cylinder, of a reciprocating valve for controlling the supply of air under pressure to the ends of said steering cylinder, a valve casing which is arranged coaxially with the pivotal axis of said outer gimbal ring and in the inner part of which said valve is slidably and transversely disposed, a crank pin carried by said outer gimbal ring, and a stirrup member interposed between said crank pin and said valve for transmitting movement from said crank pin to said valve with respect to the valve casing when relative movement occurs between said valve casing and said outer gimbal ring.
6. In a torpedo tube, the combination with the breech door, of an adjustable member mounted on said door and means for detachably connecting said member to the adjusting member of an "angle fire" device of a torpedo within said tube.
7. In a torpedo tube, the combination with the breech door, of an adjustable pointer on said door, a graduated "angle fire" dial on said door, a setting spindle in the tube and means for connecting said pointer to said spindle by the act of closing the breech door and means for detachably connecting said spindle to the adjusting member of an "angle fire" device of a torpedo within said tube.

ALBERT EDWARD JONES.
